(57) **CLAIM**

The ornamental design for a multifunctional metal fidget slider, as shown and described.

DESCRIPTION

FIG. 1 is a front, top, and left perspective view of a multifunctional metal fidget slider showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a rear, bottom, and right perspective view thereof; FIG. 9 is an exploded front view of the multifunctional metal fidget slider; and, FIG. 10 is an exploded perspective view of the multifunctional metal fidget slider. The broken lines shown in the drawings represent portions of the multifunctional metal fidget slider that form no part of the claimed design.
